UNITED STATES PATENT OFFICE

CARL A. LINDE, OF PUYALLUP, WASHINGTON

ROOF COVERING

Application filed September 13, 1928. Serial No. 305,837.

This invention relates to improvements in the construction of shake shingles and method for applying the shingles to a roof.

A prime object of this invention is to provide a shake shingle constructed in such a manner that it may be of any desired length to conform with individual tastes, length of a roof tier, or the like, and at the same time be applicable for covering roofs without removing the old shingles or otherwise therefrom.

A further object of this invention is to provide a shingle having the two longitudinal edges of different widths or thicknesses.

15 Another object of this invention is to provide a method for laying the shingles in such a manner that they will not bend or warp under varying weather conditions.

A further object of this invention is to provide a roof construction which will not bend or warp under varying weather conditions, and which may be applied over an old roof made of shingles or otherwise without removing the old coverings.

25 Other objects of this invention will appear from the following detailed description of the device and as disclosed in the single sheet of drawings which is herewith made a part of this application.

30 In the drawings—

Figure 1 illustrates a front elevational view of the lower edge of the roof, disclosing the preferred method of applying the shingles thereto.

35 Figure 2 represents a perspective view of the roof construction.

Figure 3 represents a plan view of a shake shingle constructed according to this invention.

40 Figure 4 illustrates a longitudinal edge view of Figure 4.

Figure 5 represents an end view of Figure 4.

In the construction of the shake shingle and method for applying the shingle to a roof, and as one modification of the invention, it is preferred that numeral 1 designates a shingle made of any suitable material, such as wood, slate, tile, or otherwise, and formed 45 in such a manner that one longitudinal edge

2 will be thinner than the opposite longitudinal edge 3, the shingle 1 tapering gradually from the edge 3 to the edge 2, the grain of the material preferably running lengthwise of the shingle, as clearly disclosed in Figure 3. 55

The shingle 1 is adapted to be made in any desired length, depending upon the choice of the individual or the necessities of the roof construction. The shingle in this invention is so constructed that it may be readily laid directly over old shingle members 4, thereby making it unnecessary to remove the old roofing material from a structure before applying the new shingles. 60

According to this invention, in laying the shingle 1 on a roof structure 5, it is preferred that the wide longitudinal edges of adjacent shingles be brought into approximate abutting position, as clearly disclosed in Figure 70 1, the edges being spaced apart a sufficient distance, as clearly shown at 6, for the purpose of allowing for expansion and contraction due to varying weather conditions. In like manner the narrow edges 2 are brought 75 into spaced and abutting relationship, as shown at 7.

Figure 1 discloses a roof section having assembled thereon in fixed relationship to each other a plurality of shingle members 1. 80 The lower course of shingles, as clearly shown in Figures 1 and 2, is laid having a foundation section 8, consisting of a plurality of shingles 1, laid along a supporting edge 9 of the roof, each shingle being spaced 85 from the edge 9, as clearly shown at 10. A spacing strip 11 is positioned under one longitudinal edge of the first shingle in the foundation course 8.

The shingles in the foundation course are 90 of a special length in order to allow for the proper laying of the first course 12, which is assembled as clearly shown in the figures of drawings having the narrow and thick edges approximately abutting each other. 95

The roof construction according to this invention will be primarily a plurality of covering members each member having relatively thin and relatively thick longitudinal edges, as clearly disclosed in Figures 3, 4 and 100

5, the covering members being arranged in overlapping courses parallel to the eaves and having the thick edges of the members of one set of alternate courses overlapping the thin edges of the members in the same courses respectively, the thin edges of the members of the other set of alternate courses overlapping the thick edges of the members in the same courses, while the adjacent overlapping courses are so staggered with respect to each other that the overlapping thick edges of the members of one course are substantially abutted by the overlapping thick edges of the members of the above adjacent course will be substantially abutted by the overlapping thin edges of the next above adjacent course.

The modification of this invention, as illustrated in the drawings and above described, provides a shingled or covered roof construction, wherein the shingles are of such a form and applied in such a manner that they will not warp or bend under changing weather conditions, owing primarily to the fact that one longitudinal edge of the shingle and a transverse portion thereof are held simultaneously in fixed relationship to the roof.

Whenever it is desired to shingle directly over an old covering of a roof, this invention provides a shake shingle particularly adapted for the purpose, it being formed having a thin and thick longitudinal edge, and laid in courses, the shingles in each course being arranged in staggered relationship to the shingles in the adjacent courses, a portion of two edges only of the shingle being free when in fixed position on the roof.

One of the prime objects of this invention is that the shingles may be placed over old roofs without removing the original roofing material, thereby saving considerable expense in recovering the roof and at the same time adding to the leak resisting qualities of the roof construction.

The method of laying the shingles is speedy and efficient, and the completed roof construction eliminates all possibility of leakage under normal conditions.

It will be understood that many changes and modifications may be made in the form of embodiment of the invention within the scope of the following claim without departing from the spirit of the invention.

What I claim is:

In a roof construction, a plurality of covering members, each member having a relatively thin and a relatively thick longitudinal edge, the covering members being arranged in overlapping courses parallel to the eaves with the thick edges of the members of one set of alternate courses overlapping the thin edges of the members in the same courses respectively, the thin edges of the members of the other set of alternate courses overlapping the thick edges of the members in the same courses respectively, the adjacent

overlapping courses being so staggered with respect to each other that the overlapping thick edges of the members of one course are substantially abutted by the overlapped thick edges of the members of the above adjacent course, and so that the overlapping thin edges of the members of the said above adjacent course will be substantially abutted by the overlapped thin edges of the members of the next above adjacent course.

In testimony whereof I affix my signature.

CARL A. LINDE.
